J. C. GOODING

FIREPROOF PARTITION

Filed April 19, 1922

J. C. Gooding Inventor

By *Cahow & Co.*
Attorney

UNITED STATES PATENT OFFICE.

JAMES C. GOODING, OF WELLSTON, OHIO.

FIREPROOF PARTITION.

Application filed April 19, 1922. Serial No. 555,580.

To all whom it may concern:

Be it known that I, JAMES C. GOODING, a citizen of the United States, residing at Wellston, in the county of Jackson and State of Ohio, have invented a new and useful Fireproof Partition, of which the following is a specification.

This invention relates to fire proof building walls and partitions.

10 The object of the invention is to provide a light, strong partition which is substantially sound proof, economical in construction, highly fire resistant, has a high percentage of salvage value when removed and rebuilt, and which can be plastered and decorated to match the walls and ceilings to which it joins.

Another object is to provide a fire proof partition which has a maximum strength and 20 rigidity with a minimum use of material and which can be easily and quickly erected and may be set up on the floor of a building and divide the space in any desired manner after the erection of the building.

25 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

35 In the accompanying drawings:

Figure 1 represents a horizontal section showing the invention applied to a corner stud.

40 Fig. 2 is a similar view showing the application of the invention to a right angle partition stud.

Fig. 3 is a similar view of a stud constructed in accordance with this invention, 45 with the wooden bucks for door and sash openings arranged in connection therewith.

Fig. 4 is a cross partition stud embodying the invention.

Fig. 5 is a similar view showing a ceiling 50 and starting wall plate.

Fig. 6 is a similar view showing the application of the invention to a stud, and

Fig. 7 is a similar view showing one ap-

plication of the invention to the floor and finishing wall plate.

55 In the embodiment of the invention illustrated in Fig. 1, a corner stud is shown comprising a wooden core 1 L-shaped in cross section and encased in a metal sheathing 5 which is folded to provide an obliquely disposed longitudinally extending rib 6 arranged at the outer corner of the casing and also to form ribs 7 and 8 substantially L-shaped in cross section, the free arms 7^a and 8^a respectively, being arranged parallel 60 with the side walls of the sheathing thereby forming substantially U-shaped seats to receive plates 12 and 15 composed of plaster board or other suitable material.

65 The sheathing at the inner corner of the stud is folded as shown at 11 to provide U-shaped seats 9 and 10 which open in planes at right angles to each other and are designed to receive plates 13 and 14 of plaster board or other suitable material 70 which constitute the inner walls of the partition, the outer walls being formed by the right angularly disposed plates 12 and 15.

75 After the plates 12, 13, 14 and 15 have been placed in position as shown in Fig. 1, a coating of plaster 16 is arranged thereover completely embedding the sheathing ribs which ribs operate as anchors for the plaster. This coating may be decorated in any desired manner.

80 Air spaces 17 and 18 are formed between the spaced side walls of the partition and another air space 19 is formed between the sheathing and the core at the inner corner of the core where the two arms thereof join each other.

85 The folding of the metal to provide the ribs which constitute the outer walls of the seats for the plates in connection with the core 1 which is preferably constructed of hard wood provide a structure as strong as 90 metal and wood combined can make it.

95 It will be observed that there are no protuberances at the points where the plaster boards enter the grooves or seats, and hence, a very small quantity of plaster will 100 be required to produce a covering 16 thereby cheapening the construction of the wall.

105 In the form shown in Fig. 2, the invention is applied to a right angle partition stud which comprises a hard wood core 1^a shown substantially T-shaped in cross sec-

tion and encased by a metal sheathing 5^a folded to provide on the outer wall of the head portion of said sheathing oppositely opening board receiving seats 20 and 21, 5 the folded portion of the sheathing providing doubled outer walls for the seats which greatly strengthens them.

The sheathing 5^a is folded at the corners provided at the junction of the head of the 10 core with its shank to provide plate receiving seats 22 and 23 and 22^a and 23^a respectively, the seats of the respective pairs opening in planes at right angles to each other to receive plates 24 which may be 15 composed of plaster board or other suitable material. This folding of the sheathing to form the seats 22, 23, 22^a and 23^a provide air spaces 25 and 26 at the corners of the stud formed by the junction of the 20 head with the shank thereof.

The outer side walls of the seats just above described are formed of double thickness as shown at 27 by folding of the casing at these points.

25 After the plates 24 have been inserted in the seats 20, 21, 22, 22^a, 23 and 23^a, they are covered by a suitable coating of plaster shown at 28.

In Figs. 3 and 6, the invention is shown 30 applied to studs each of which has a hard wood core 1^b and 1^c respectively, which are of the same shape, being substantially rectangular in cross section. Each of these cores is encased by a metal sheathing 29 the 35 side walls of which are folded to provide lateral extensions 30 and 31 which are T-shaped in cross section, the member 30 forming seats 32 and 33 while the member 31 forms seats 34 and 35 to receive plates 40 36. In Fig. 3 one pair of plates only are employed, the opposed face of the said stud having mounted thereon a wooden buck 37 for a door or sash opening.

In Fig. 4, the invention is shown applied to a cross section, the core 38 of which is constructed of hard wood and is made cruciform in cross section, and encased in a metal sheathing 39. This sheathing 39 is bent and folded at the corners formed by 50 the arms of the cross to provide plate receiving seats 40 and 41 which open in planes at right angles to each other and are designed to receive plaster board plates 42 over which is arranged a coating 43 of 55 plaster. The construction of this sheathing and the arrangement of the boards at the four corners is exactly the same and hence, one only need be described in detail.

In Fig. 5, a ceiling and starting wall 60 plate is shown comprising a hard wood core substantially rectangular in cross section and encased on three sides by a metal sheathing 45 which is U-shaped in cross section, the arms 46 thereof having seats 47 65 carried thereby and opening in a direction

opposite to the casing 45, said seats 47 having their outer walls doubled as shown at 48. These seats 47 are designed to receive plaster boards or plates 49 over which is arranged a plaster coating 50.

In the form shown in Fig. 7, a floor or finishing wall plate is shown comprising a hard wood core 51 encased in a metal sheathing 52, similarly constructed to the sheathing 45 of Fig. 1, except that the outer walls of the seats 52 thereof are made single instead of double, these seats 53 support boards 54 over which is arranged a plaster coating 55.

In the use of the partitions and side walls 80 embodying this invention, when constructing a partition wall, the partition is first lined off then a plumb line is raised to the ceiling at the wall where the partition starts and the ceiling plate then lined off. Then the floor, wall and ceiling plates are next placed in position and the plaster or analogous plates are set into the grooves or seats on one side of the ceiling plate and against the shoulder on the floor plate and then forced into the grooves in the wall plate. This operation is then repeated on the opposite side of the partition. The seats of a studding are then placed over the plates or boards and the studding driven up, tight 90 and toe-nailed to the ceiling plate and to the floor plate. This operation is repeated according to the number of panels required by the partition.

From the above description it will be 100 obvious that with some slight variations, these metal encased studs and plates may be used to completely construct a building, the walls, floors, ceilings and roof, being formed therefrom. The wooden cores used, permit fastening of any wooden trimming or 105 finishing to the walls without any special ground, furring, or blocking being employed.

It will also be seen that any kind of material desired may be used in the construction of the plates which are described as composed of plaster board, and that they may vary in thickness for either the outside or inside of the walls of all cases leaving non-conducting air chambers which render the partition or wall substantially 115 sound-proof.

I claim:—

1. A wall of the class described comprising a stud in the form of a rigid, solid core, a metal sheathing encasing said core and folded to form combined plate receiving seats and anchors, some of the walls of said seats being double, the members of which lie in contact with each other whereby the walls are reinforced to resist strains.

2. A wall of the class described comprising a stud in the form of a rigid, solid core, a metal sheathing encasing said core and 130

folded to form combined plate receiving seats and anchors, some of said seats being so formed and spaced from the core to provide air spaces between the sheathing and the core, plates mounted in said seats, and a coating encompassing said plates and sheathing.

In testimony that I claim the foregoing as my own, I have hereto affixed my signature in the presence of two witnesses.

JAMES C. GOODING.
